CLAIM

The ornamental design for an adjustable angle plow attachment, as shown and described.

DESCRIPTION

FIG. 1 is a perspective view of the top, rear and left sides of an adjustable angle plow shown in a typical use configuration;

FIG. 2 is a rear elevation view of the adjustable angle plow; FIG. 3 is a right side elevation view of the adjustable angle plow;

FIG. 4 is a front elevation view of the adjustable angle plow; FIG. 5 is a left side elevation view of the adjustable angle plow;

FIG. 6 is a top plan view of the adjustable angle plow; and, FIG. 7 is a bottom plan view of the adjustable angle plow. The broken-lines in the above-described figures are for illustrative purposes only, and form no part of the claimed design.

The claimed adjustable angle plow may be used in conjunction with the plowing of snow and similar materials by attachment to a skid steer or similar loader.

1 Claim, 7 Drawing Sheets
